UNITED STATES PATENT OFFICE.

ANNA C. DAVIS, OF SIOUX CITY, IOWA.

MUSICAL NOTATION.

No. 828,020.

Specification of Letters Patent.

Patented Aug. 7, 1906.

Application filed February 15, 1904. Serial No. 193,752.

To all whom it may concern:

Be it known that I, ANNA C. DAVIS, a citizen of the United States, residing at Sioux City, in the county of Woodbury and State 5 of Iowa, have invented a New Staff and a Method of Manipulating the Same for the Expression of Music, of which the following is a specification, reference being had to the accompanying drawings.

10 This invention relates to music, and has for its object to provide certain new and useful improvements in musical notation whereby the reading of music in general is facilitated and in particular to facilitate the transposition from one key to another with little or no mental effort and practically unconsciously.

15 In carrying out the invention I propose to retain the syllable or "do, re, mi" method of reading, and in this connection employ an improved staff having a fixed tonic or "do" syllable indicating element, whereby every note may be conveniently read in accordance with its position with respect to the tonic- 25 indicating element.

20 To provide for the changing of keys, I propose to shift the position of adjacent staff portions in direct relation with the raising or lowering of the pitch of the new key, as will be 25 hereinafter more fully described, shown in the accompanying drawings, and particularly pointed out in the appended claims.

30 In the drawings, Figure 1 is a view of the improved staff employed in connection with the present system of musical notation. Fig. 2 is a view of the improved staff including notes thereon and showing portions of the staff shifted to indicate change of keys.

35 In setting forth my invention I will first 40 explain my improved staff and then the method of using the same.

The improved staff employed in connection with my method of musical notation consists of five parallel lines designated in the 45 drawings by the reference characters 1, 2, 3, 4, and 5, of which the lowermost and uppermost lines are distinguished from the intermediate lines preferably by being printed as heavy black lines with the intermediate lines 50 narrower or lighter. The two uppermost lines are arranged in closer relation than the first four lines, the latter being spaced at regular intervals, as in the ordinary staff, and the usual character of notes being placed upon 55 all of the lines and the first three spaces only, the narrow space at the top of the staff

not being used. With this form of staff each heavy black line indicates the tonic (or octave) or "do" syllable, and the intermediate spaces and lines indicate the succeeding 60 syllables in the usual order with the exception of the uppermost and smaller space, within which notes never appear. In reading music written upon this staff any tone may be taken as the tonic, and wherever a note 65 appears upon either of the black lines it will be understood that this note indicates the tonic or the syllable "do" of the scale and all other notes may be readily read in accordance with their positions upon the different 70 lines and spaces. When a change of key occurs, it is not necessary to indicate the same by signatures or other suitable characters; but the staff is shifted either up or down, according as the new key is higher or lower 75 than the previous key, the black or tonic line of the new staff being shifted to form a continuation of that line of the previous staff which indicates the tone that is now to be used as the tonic, or the black line is shifted to 80 a position opposite one of the spaces of the previous staff, according to the location of the new tonic. This feature is directly in line with what actually occurs in changing from one key to another, as the change is 85 always to a higher or lower pitch accordingly as the new tonic is higher or lower than the original tonic.

Referring now to Fig. 2, there has been 90 illustrated an initial staff designated in general A, and for sake of convenience it will be supposed that the tonic tone indicated by the black line of this staff is pitched upon D-natural, or, in other words, the key of D-major. When a change in key occurs—say, for instance, to the key of B-minor—the staff is then 95 shifted downwardly, as indicated at B, to bring the uppermost black line thereof in alinement with the upper full space of the staff A, which indicates that the syllable "do" 100 or tonic of the new key has the pitch of "la" of the former staff and key. In reading the music upon the staff B the pitch of the first note in said staff is obtained by referring to the line or space of the previous staff, which 105 is in alinement with the note, and then sing or play the note with the pitch indicated by said line or space, but calling the note by the syllable indicated by its position in the new staff. For instance, the first note 6 of the 110 new staff is in the first space thereof, and therefore represents the syllable "re," and it

is opposite the next to the uppermost or fourth line of the former staff, which indicates the syllable "si" on said staff, wherefore the note 6 should be pitched upon "si" 5 of the former staff, but should be called "re" in accordance with its position upon the new staff. After having obtained the pitch of the first note the remaining notes are sung or played in the syllable method, according to 10 their positions upon the staff, with the two black lines always indicating "do" or the tonic of the key. It will here be explained that the pitch or key of the initial portion of the staff should be indicated in some appropriate manner—such, for instance, as "D Ma," 15 as indicated at 7 in Fig. 2, which indicates that the pitch is that of the key of D-major—in order that the pitch of "do" or the tonic of the key indicated by the black lines may be 20 readily obtained from a tuning-fork, piano, or other musical instrument. When a change in key occurs, it may be appropriately indicated, as at 8, in the staff portion B, wherein the expression "B Mi" indicates 25 that the new key is B-minor; but it is of course apparent that it is not necessary to thus indicate the key, for the reason that when the pitch of the first note of the new staff is obtained the following notes are read 30 in the "do, re, mi" method, with the tonic or "do" syllable always occurring on the black lines. From the foregoing explanation it will be understood that when the pitch of the first note in any staff portion is obtained the following notes may be conveniently read irrespective of the key and irrespective of any other staff portion. In other words, each staff portion is complete in itself and entirely independent of other staff portions so far as the 40 reading of the notes contained thereon is concerned, for the reason that the tonic or "do" syllable always maintains a fixed position upon each and every staff portion, the only difference residing in the fact that the staff is 45 shifted either up or down in accordance with the raising and lowering of the tonic. Should the first tone in the new key not be found on the previous staff, the tone should be indicated by an appropriate accidental mark placed 50 upon the previous staff portion—such, for instance, as a flat character 9 placed upon the line or space in alinement with the first note of the new staff, which in the present instance is the note 10, occupying the third 55 line of the new staff, wherefore the flat character should of course be placed upon the fourth line of the previous staff portion. To obtain the pitch of this note, reference is had to the line of the previous staff in alinement with the degree of the shifted staff portion 60 upon which the note occurs, which in the present instance is the fourth or next to the upper line and indicates the syllable "si," which when flattened is of course "se," the 65 pitch of the note 10; but said note should be

called "sol," in accordance with its position on the new staff.

By reason of the fact that the "do" syllable or tonic bears a fixed relation upon the staff and always occurs upon the upper and lower lines thereof a plurality of staffs in vertical succession may be employed, as each staff merges regularly into each of the upper and lower staffs, the lower black line of the upper staff serving as the upper black line of the lower staff, wherefore it is not necessary to employ additional or ledger lines between upper and lower staffs. Moreover, it is not necessary to distinguish the treble-staff from the bass-staff, in view of the fact that the 70 tonic or "do" syllable always occupies the same position upon the staff, and therefore the bass and treble staffs have the notes arranged thereon with respect to the upper and lower black lines as the tonic or "do" syllable of the key and not with respect to the position of the shiftable tonic, as in the usual method of musical notation. Where it is not desirable to add a complete staff above or below the main staff or staffs, ledger-lines 75 80 85 90 95 may of course be employed, as indicated in Fig. 1 of the drawings.

From the foregoing description it will be understood that the present staff includes five note-bearing lines and three note-bearing 95 spaces, thereby producing an eight-degree staff wherein the lowermost and uppermost lines form marginal degrees representing the same scale degree which is the tonic and the octave thereof, wherefore it will be understood that the degrees of the staff correspond with those of a scale-octave and multiples thereof.

Having thus described my invention, what I claim as new, and desire to secure by Letters Patent, is—

1. A musical staff having a portion shifted to bring its degrees into alinement with other degrees of the adjacent preceding portion of the staff.
2. A musical staff made up of five lines and four spaces, the uppermost and lowermost lines being distinguished from the other lines, the three lower spaces being each of the same width and the uppermost space being narrower than the other spaces, a portion of the staff being shifted to bring its degrees into alinement with other degrees of the adjacent preceding staff portion.
3. A musical staff including eight degrees only and having a portion shifted to bring its degrees into alinement with other degrees of the adjacent preceding portion of the staff.
4. A diatonic-scale staff having a change of key indicated by a staff portion which is shifted vertically with respect to the adjacent preceding staff portion, with certain of the degrees of the two staff portions merged into one another.
5. A diatonic scale-staff consisting of five

degree-lines, three degree-spaces, and a single space differing in width from the degree-spaces, the top and bottom lines of the staff being broader than the other lines, and a portion of the staff being shifted vertically to bring its degrees into alignment with other degrees of the adjacent preceding staff portion.

6. A music-score having its staff provided with disaligned staff portions, each of which portions is composed of lines having fixed relative diatonic designations, the corresponding lines of different staff portions having the

same diatonic designations, whereby those lines of different staff portions which are designed to receive, respectively, the tonic notes of the keys occupy relative positions corresponding to the difference in pitch between the tonics of those scales. 15

In testimony whereof I have signed my name to this specification in the presence of two subscribing witnesses.

ANNA C. DAVIS.
